UNITED STATES PATENT OFFICE.

CYRUS A. HAAS, OF ST. LOUIS, MISSOURI.

DESIGN FOR A LAMP-BODY.

SPECIFICATION forming part of Design No. 36,029, dated August 26, 1902.

Application filed July 3, 1902. Serial No. 114,326. Term of patent 14 years.

To all whom it may concern:

Be it known that I, CYRUS A. HAAS, a citizen of the United States, residing at St. Louis, in the State of Missouri, have invented and produced a new, original, and ornamental Design for Lamp-Bodies, of which the following is a specification, reference being had to the accompanying drawing, forming a part hereof.

In the accompanying drawing the figure o represents a view in elevation of an incandescent-lamp body constructed substantially in accordance with this design.

As shown in the drawing the leading feature of my design consists in a base portion a, substantially circular at the top and having an outer shell portion formed of a plurality of downwardly and inwardly extending leaf portions b, terminating at their respective lower ends in scrolls c and at their upper ends o in scrolls d, such base portion being also provided with upwardly and outwardly extending flanges e, arranged substantially in a circle at the top portion thereof, an upper substantially cylindrical shell f, arranged above

such base portion and provided with a pipe g, 25 extending downward therefrom to the base and connecting such base and upper shell, a substantially spherical globe h, arranged between such base and shell, a substantially hemispherical hood i, having projections j on 30 its lower edge and arranged above and extending over the top of the upper shell, and a plurality of scrolls k, extending longitudinally of the shell portion and outward from the upper portion of the shell to the edge of 35 the hood.

Having thus described my invention, what I regard as new and ornamental, and desire to secure by Letters Patent, is—

The ornamental design for a lamp-body, as 40 herein shown and described.

In testimony whereof I have signed my name to this specification in the presence of two subscribing witnesses.

CYRUS A. HAAS.
